(57) **CLAIM**

The ornamental design for a corner bracket fitting for use in an attachment system, as shown and described.

DESCRIPTION

FIG. 1 is an upper front perspective view of the first embodiment of a corner bracket fitting for use in an attachment system of the claimed design;

FIG. 2 is an upper back perspective view of the corner bracket fitting for use in an attachment system of FIG. 1; FIG. 3 is a front view of the corner bracket fitting of FIG. 1; FIG. 4 is a back view of the corner bracket fitting of FIG. 1; FIG. 5 is a bottom view of the corner bracket fitting of FIG. 1;

FIG. 6 is a top view of the corner bracket fitting of FIG. 1; FIG. 7 is a left view of the corner bracket fitting of FIG. 1; FIG. 8 is a right view of the corner bracket fitting of FIG. 1; FIG. 9 is an upper front perspective view of the second embodiment of a corner bracket fitting for use in an attachment system of the claimed design;

FIG. 10 is an upper back perspective view of the corner bracket fitting for use in an attachment system of FIG. 9; FIG. 11 is a front view of the corner bracket fitting of FIG. 9;

FIG. 12 is a back view of the corner bracket fitting of FIG. 9; FIG. 13 is a bottom view of the corner bracket fitting of FIG. 9;

FIG. 14 is a top view of the corner bracket fitting of FIG. 9; FIG. 15 is a left view of the corner bracket fitting of FIG. 9; and,
FIG. 16 is a right view of the corner bracket fitting of FIG. 9.

The broken lines in the drawings illustrate portions of the corner bracket fitting for use in an attachment system and form no part of the claimed design.

1 Claim, 16 Drawing Sheets
